Primary Examiner — Mary Ann Calabrese*Assistant Examiner* — Catherine Ho(74) *Attorney, Agent, or Firm* — Davis & Bujold PLLC;
Michael J. Bujold(57) **CLAIM**

We claim the ornamental design for a vending machine, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top front right perspective view of the first embodiment of a vending machine shown in color, showing our new design;

FIG. 2 is a top front elevational view thereof;

FIG. 3 is a top front right perspective view of the second embodiment of a vending machine; and,

FIG. 4 is a top front elevational view thereof.
